HAND TOOL

Ernest C. Neal, Chicago, Ill., assignor of one-half
to Elmer Brandell, Chicago, Ill.

Application May 12, 1949, Serial No. 92,896

5 Claims. (Cl. 30—189)

1

The present invention relates in general to power multiplying lever systems, and has more particular reference to an improved lever system especially well suited for incorporation in cutters, pliers, nippers, shears and the like; the present invention being particularly well adapted for use in providing powerful hand tools of relatively small size and convenient usage.

An important object of this invention is to provide compact, inexpensive, simple and efficient mechanism having closable jaws, wherein the application of relatively little force on the instrument will exert relatively powerful jaw closing forces.

Another important object is to provide a lever mechanism of the character mentioned, which increases its power multiplying effect during its operating stroke; a further object being to provide a lever system in which the power multiplying effect increases to a maximum during the initial stages of the operating stroke of the system, whereby, when applied as a cutter, a maximum cutting effect of the cutter jaws may be attained during, preferably at the medial portions of, the operating stroke of the device.

Another important object is to provide a compound lever system providing for the movement of a working lever, about its fulcrum, by the application of force, to a portion of the working lever, through the medium of an auxiliary lever member adapted to apply force to a bearing portion of the working lever, at progressively increasing distance from the fulcrum thereof, during the working stroke of the system; a further object being to form such bearing portion as a cam surface, along which a cam following portion of the auxiliary lever is adapted to move during the operation of the system.

Another important object is to provide the auxiliary lever with a pair of cam following portions adapted successively to bear upon and travel along the cam surface of the working lever during the working stroke of the apparatus.

Another important object is to utilize roller means on the auxiliary lever for camming purposes with the work lever.

Another important object is to so form the levers and locate the pivots thereof, and to shape the cam surface of the working lever, so as to determine the angle of attack of the cam following portion or portions on the cam surface, whereby to apply the force of the auxiliary lever as a wedging action on the work lever; a further object being to decrease such angle of attack and thereby increase such wedging action during the

2

operating stroke of the apparatus; a still further object being to cause application of the force of the auxiliary lever to the cam surface initially in a direction substantially normal thereto, while progressively decreasing the angle of attack during the operating stroke.

Another important object resides in controlling power multiplication in a compound lever system by forming the cam surface of the work lever as a curved surface of desired configuration to obtain a desired variant power multiplying ratio during the working stroke of the system.

Another important object resides in providing an unusually powerful cutter or pliers for hand operation, and embodying the novel compound leverage system of the present invention.

The foregoing and numerous other important objects, advantages, and inherent functions of the invention will become apparent as the same is more fully understood from the following description, which, taken in connection with the accompanying drawings, discloses preferred embodiments of the invention.

Referring to the drawings:

25 Fig. 1 is a sectional view taken longitudinally through a cutter device embodying the present invention, the parts being shown in relatively open position, as at the commencement of a cutting stroke;

30 Fig. 2 is a fragmentary view of the device, shown in Fig. 1, illustrating the parts in partially closed position, as at a medial position during the operating stroke of the device;

35 Fig. 3 is a fragmentary view, similar to Fig. 2, showing the parts in fully closed position, as at the end of the operating stroke of the device;

40 Fig. 4 is a sectional view taken substantially along the line 4—4 in Fig. 1;

Fig. 5 is a sectional view taken substantially along the line 5—5 in Fig. 2;

45 Fig. 6 is a sectional view taken substantially along the line 6—6 in Fig. 3; and

Fig. 7 is a fragmentary view, similar to Figs. 2 and 3, illustrating a modified form of the invention.

To illustrate the invention, the drawings show a cutting device 11 particularly adapted for manual operation, the device specifically shown being a wire or rod cutter, although it will be apparent that the invention is not necessarily limited to the specific use to which it may be put, the same being applicable in shears of all sorts, pliers, nippers, and other devices wherein power multiplication is desirable.

As shown, the device 11 comprises a main frame

12, which may conveniently be formed as a sheet metal stamping. At one end the frame is formed to provide a jaw 13. This jaw may, of course, be formed in any suitable, preferred or convenient fashion, but, as shown, it comprises a block 14, preferably of hardened cutting material such as tool steel, the block being formed to desired shape to provide a cutting edge 15 and secured in the main frame 12 in any suitable fashion, as by welding or riveting the same in place. Adjacent 10 the block 14 the main frame provides a mounting for a pivot pin 16, secured at its opposite ends, as in a pair of spaced apart panel portions or wings 17 of the main frame.

The pin 16 forms a fulcrum pivot for a lever member 18, which comprises the working lever of the system. This working lever extends between the panels 17 of the main frame, is pivoted on the pin 16, and formed at one end to provide a jaw 19 in position to register and cooperate with the jaw 13 and to close on and to open with respect to said jaw, in response to relative angular movement of the lever 18 with respect to the main frame about the fulcrum pivot 16.

The lever member 18 may conveniently comprise a formed block of tool steel or other hard cutting material, and may be formed with a cutting edge 20 in position to cooperate, in registering alinement, with the cutting edge 15 when the jaws are in the relatively closed position shown in Fig. 3. On the side of the pivot 16 remote from the jaw 19, the lever member 18 may be formed with a thrust surface 21, and may be normally urged toward jaw open position on the fulcrum pivot 16 by biasing spring means 22, preferably comprising a helical tension spring, anchored at its opposite ends, respectively on the lever 18 and on the main frame 12 between the wings or panels 17 thereof. This spring normally serves to yieldingly urge the lever 18 toward relatively open position on the main frame 12, as shown in Fig. 1.

To close the working lever 18 against the influence of the spring 22, a manually operable auxiliary lever 23 may be provided. This lever may conveniently be mounted for pivotal movement on and with respect to the main frame 12, as by means of a pivot pin 24 secured at its opposite ends in spaced apart extensions 25 of the panel portions 17 of the main frame.

The handle 23, like the main frame, may be formed of sheet metal and may provide journal means, such as the ears 26, for pivotally mounting the auxiliary lever 23 on the pin 24 in position extending between the panel portions 17 of the main frame. On one side of the pivot 24 the lever 23 provides a handle, by means of which power may be applied thereto in order to turn the same upon the pivot 24 in the performance of the operating stroke of the lever system. To this end, the main frame 12, at the end thereof remote from the jaw 13, may be formed to provide a handle 27, whereby to hold or anchor the main frame to facilitate the movement of the handle 23 during the operation of the device. Preferably, the members 23 and 27 form cooperating handles that may be drawn together by the contraction of the hand of the operator of the device in the performance of the operating stroke.

The auxiliary lever 23 is provided with bearing means for engagement with the thrust surface 21 of the work lever 18, such thrust surface 21 providing a cam surface, and such bearing

means on the auxiliary lever preferably comprising a roller or rollers 28, 28'. The rollers 28, 28' may conveniently be journaled on pins 29, 29' mounted at their opposite ends in extensions 30 of the lever 23. The roller means 28, 28' is positioned to engage and ride upon the cam surface 21 of the work lever. The rollers thus form bearing means for imparting thrust upon the thrust surface 21 of the working lever; and while it is entirely feasible to employ non-rotary or fixed bearing members on the auxiliary lever, it is preferable to employ roller means as shown to facilitate free movement of the bearing element or elements along the thrust surface. It will be understood, however, that the invention is not necessarily restricted to the roller form of the bearing or thrust elements 28, 28', specifically shown.

In moving from the fully open position, shown in Fig. 1, during the operation of the device, closing movement of the auxiliary lever 23 will cause the roller 28 to move from its position of initial engagement with the surface 21 in a direction away from the fulcrum pivot 16 of the working lever, thereby increasing the leverage arm between said fulcrum pivot and the point of engagement of the roller 28 on the cam surface 21. During the operating stroke of the mechanism, also, it will be noted that the angle of attack, or thrust of the roller 28 upon the surface 21, takes place, in the illustrated embodiment, substantially at right angles to such surface. This angle of attack, however, during the operating stroke of the apparatus, progressively decreases, thereby effecting a wedging or toggle action between the auxiliary lever 23 and the work lever 18, with the result that power multiplication very substantially increases during the operating stroke of the apparatus. This action is exceedingly valuable in small, portable cutting tools, especially tools for cutting relatively heavy steel rods. The apparatus, of course, may be constructed with but one roller 28 to operate on the cam surface 21 throughout the entire operating stroke of the device. To this end, it is merely necessary to provide sufficient length in the lever 18 so that the roller 28 will not leave the cam surface 21 during the operating stroke of the device.

As shown, however, an exceedingly compact and effective apparatus may be provided by forming the working lever 18 so that the roller 28 will reach the fulcrum pivot remote end of the cam surface 21 and become disengaged therefrom during and prior to the completion of the operating stroke. In such arrangement, the roller 28' is so positioned on the lever as to come into engagement with the cam surface 21 as the roller 28 becomes disengaged from such surface, so that the roller 28' may transfer power from the auxiliary lever 23 to the work lever 18 during the terminal portions of the operating stroke of the device. In performing its function, the roller 28', after engaging the cam surface 21, will roll thereon in a direction away from the fulcrum pivot 16, thereby increasing the power multiplying effect during the course of its operating movement on the cam surface. During the course of such operating movement of the roller 28', the angle of attack of the auxiliary lever on the work lever decreases, thereby increasing the wedging effect, in fashion previously noted in connection with the operation of the roller 28.

It will be seen from the foregoing that, where a plurality of successively operating rollers 28,

28' are utilized to transfer power from the auxiliary to the working lever, power multiplication is initially accomplished during the working stroke, by the action of the roller 28, power multiplication reaching a maximum as said roller reaches the end of the cam surface 21. Maximum power at the jaws 13, 19, in response to a given force applied on the auxiliary lever 23, is thus exerted during the medial stages of the operating stroke of the device. This result is particularly desirable where the cutting of rods is involved, since the maximum resistance to cutting, in rods, is encountered midway of the cutting stroke. After such maximum cutting resistance point is reached, in the cutting of rods, 15 resistance to cutting falls off rapidly so that the required force for completing the cut may be materially reduced. This is amply supplied in the present invention by the roller 28'.

The multiple roller construction not only allows the use of a shorter working lever 28 at its cam surface end, thereby affording compact structure, but also provides a cutter of maximum efficiency for the cutting of relatively large diameter rods, in which the cutting action is initially accomplished by the roller 28, and finally by the roller 28'. The structure also affords maximum cutting efficiency where small section rods of tough material are required to be severed. With such small section rods the roller 28' provides maximum power multiplication toward the medial and end portions of its operating stroke.

As shown more particularly in Fig. 7, the cam surface 21, whether single or multiple roller structure is involved, may be curved in order to obtain a desired power multiplication at any stage during the operating stroke of the device. Where the cam surface is curved, as shown in Fig. 7, power multiplication will increase at a rate different from that at which it increases where the cam surface 21 is substantially flat, as shown in Figs. 1-3. This characteristic may be advantageously utilized where it is desired to accomplish particular relative multiplication during selected portions of the operating stroke.

In order to provide a stop for limiting the opening movement of the device, under the influence of the biasing spring 22, the main frame 12 may be provided with an offset shoulder 31 in position to cooperatively engage with an extension on the auxiliary lever 23, such extension in the illustrated embodiment comprising the roller 28'.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the forms herein disclosed being preferred embodiments for the purpose of illustrating the invention.

The invention is hereby claimed as follows:

1. A hand tool comprising a main frame forming a handle portion at one end and a jaw portion at the other, a work lever forming a cooperating jaw, means forming a fulcrum pivot for said work lever on said frame adjacent the jaw portion, an operating lever forming a handle, a mounting pivot on said frame for mounting said operating lever for angular movement toward said handle portion in the performance of a jaw closing stroke of the operating lever, said work lever having a cam surface thereon extending

outwardly of said fulcrum pivot toward said mounting pivot, and a pair of spaced apart bearing members on said operating lever in position, between said fulcrum and mounting pivots, to successively engage said cam surface in a direction progressively away from said fulcrum pivot during the jaw closing stroke of the operating lever, whereby each of said bearing members during its engagement with the cam surface exerts a progressively increasing force on the cam surface during its movement therealong.

2. A hand tool comprising a main frame forming a handle portion at one end and a jaw portion at the other, a work lever forming a cooperating jaw, means forming a fulcrum pivot for said work lever on said frame adjacent the jaw portion, an operating lever forming a handle, a mounting pivot on said frame for mounting said operating lever for angular movement toward said handle portion in the performance of a jaw closing stroke of the operating lever, said work lever having a cam surface thereon extending substantially radially outwardly of said fulcrum pivot toward said mounting pivot, and a pair of spaced apart bearing members on said operating lever in position, between said fulcrum and mounting pivots, to successively engage said cam surface in a direction progressively away from said fulcrum pivot during the jaw closing stroke of the operating lever, whereby each of said bearing members during its engagement with the cam surface exerts a progressively increasing force on the cam surface during its movement therealong.

3. A hand tool comprising a main frame forming a handle portion at one end and a jaw portion at the other, a work lever forming a cooperating jaw, means forming a fulcrum pivot for said work lever on said frame adjacent the jaw portion, an operating lever forming a handle, a mounting pivot on said frame for mounting said operating lever for angular movement toward said handle portion in the performance of a jaw closing stroke of the operating lever, said work lever having a cam surface thereon extending outwardly of said fulcrum pivot toward said mounting pivot, and a pair of spaced apart bearing members on said operating lever, including a main bearing member and an auxiliary bearing member spaced on said operating lever further from said mounting pivot than the main member, said members being disposed in position between said fulcrum and mounting pivots to successively engage said cam surface in a direction progressively away from said fulcrum pivot during the jaw closing stroke of the operating lever, whereby each of said bearing members during its engagement with the cam surface exerts a progressively increasing force on the cam surface during its movement therealong, said auxiliary bearing member being disposed on said operating lever in position to engage and commence its operating movement on said cam surface as the main bearing member concludes its operating movement on said cam member.

4. A hand tool, as set forth in claim 3, wherein said members are disposed in position each to initially attack the cam surface at substantial angles and thereafter at progressively decreasing angles during the movement thereof along the cam surface.

5. A hand tool, as set forth in claim 3, wherein the main bearing member is disposed in position initially to attack the cam surface in a direction substantially normal thereto and thereafter at

progressively decreasing angles of attack during the jaw closing movement of the operating lever, the auxiliary member being positioned to initially attack the cam surface at a substantial angle and thereafter at progressively decreasing angles during the movement thereof along the cam surface.
